Primary Examiner — Phillip S Hyder*Assistant Examiner* — Darlington Ly(74) *Attorney, Agent, or Firm* — Crowell & Moring LLP(57) **CLAIM**

The ornamental design for a breaker, as shown and described.

DESCRIPTION

FIG. 1 is a left, front perspective view of a breaker according to the design;

FIG. 2 is a right, rear perspective view thereof;

FIG. 3 is a left side view thereof;

FIG. 4 is a right side view thereof;

FIG. 5 is a top view thereof;

FIG. 6 is a bottom view thereof;

FIG. 7 is a front view thereof; and,

FIG. 8 is a rear view thereof.

The broken lines shown in the drawings illustrate portions of the breaker that form no part of the claimed design.

1 Claim, 6 Drawing Sheets(56)
